HENRY P. CLAUSEN, OF ROCHESTER, NEW YORK, ASSIGNOR, BY MESNE ASSIGNMENTS, TO WESTERN ELECTRIC COMPANY, OF CHICAGO, ILLINOIS, A CORPORATION OF ILLINOIS.

CALL-DISTRIBUTING TELEPHONE SYSTEM.

1,131,911.

Specification of Letters Patent. Patented Mar. 16, 1915.

Application filed June 26, 1911. Serial No. 635,296.

To all whom it may concern:

Be it known that I, HENRY P. CLAUSEN, a citizen of the United States, and resident of Rochester, county of Monroe, State of New York, have invented certain new and useful Improvements in Call-Distributing Telephone Systems, of which the following is a specification.

My invention relates to call-distributing telephone systems. In systems of this class the incoming telephone calls are automatically distributed before idle telephone operators, so that the work of the various operators is equalized, and so that the subscribers' calls receive prompt attention.

The object of my invention is to combine a call-distributing system with a regular common battery multiple manual system so as to retain the advantages of both types of systems.

It is found in practice that about 50 per cent. of the incoming telephone calls originate with about 15 per cent. of the subscribers; in other words, one-half of the operators' time is occupied in taking care of the calls arising upon about one-seventh of the telephone lines. In accordance with my invention I select these busy telephone lines—those originating, say, five calls an hour or over—and connect them with automatic distributor switches at the central office, leaving the other lines to terminate before operators in the usual way.

My system further provides means for preventing a call which originates on one of the distributed lines from appearing before an operator who at that time has one or more unanswered manual calls upon each division of her section of the switchboard.

My system further provides means for preventing a call which originates upon a distributed line from appearing before an operator who at that time has one unanswered distributed call upon each division of her section of the switchboard; in other words, my system provides means for distributing, before the regular manual operators who are not burdened with unanswered calls of either class, the calls originating upon the busiest lines in the exchange.

One advantage of this system is the economy of installation. Switches for automatically distributing incoming calls can

not be installed at as low a cost as the apparatus associated with the line of a regular multiple switchboard, and it is, therefore, extravagant and unnecessary to provide distributing switches for lines which originate an average of less than, say, five calls per hour.

Another advantage of my system is the incentive which it furnishes the operators for answering calls promptly. Each operator may be in charge of 100 regular incoming lines and may have, in addition to those, 10 call-distributing trunks. The operators may be paid their regular salaries for handling the regular lines and may be paid piece-work rates in accordance with the number of calls answered upon their call-distributing trunks. It will be seen that no call will appear upon one of these call-distributing trunks when more than one unanswered call appears before the operator, either among her regular lines or among the call-distributing trunks. The operator will therefore endeavor to answer all calls promptly so that her call distributing trunks will at all times be free to receive the calls of distributed lines. This results in prompt attention and quick service.

Another feature of my invention is the application of the call counter, making the piece rate above described possible.

Other features of my invention will be pointed out in the following description and claims.

My invention is illustrated in the accompanying drawings, in which all apparatus is shown in its normal or unactuated condition.

Figure 1 illustrates two lines terminating in automatic distributing switches and one regular telephone line. Fig. 2 illustrates the answering and multiple jacks of the regular telephone line, the multiple jacks for the distributed telephone lines, and the operator's call distributing trunk circuits to which these lines have access, also the circuits and apparatus for barring calls on the call-distributing trunk when unanswered calls appear before the operator, and Fig. 3 illustrates the operator's cord circuit for use with either the regular manual or the call-distributed trunks, and also illustrates a regular subscriber's line with which the cords may be connected.

Subscribers' stations 1, 2, 3 and 4 are each provided with the regular common battery equipment, consisting of a condenser 5 and ringer 6 in a bridge between the telephone line conductors 7 and 8, and of the transmitters 9 and receivers 10 in a bridge maintained normally open by the contacts of the switch-hooks 11. The limb 7 of subscriber's line extends from substation 1 to the central office and thence through contacts 12 and 13 of cut-off relay 14 and through the coil 15 of line relay 16 to conductor 17, which extends to the live pole of battery A. The limb 8 of this subscriber's line extends to the central office and thence through contacts 18 and 19 of cut-off relay 14 and the coil 20 of cut-in relay 21, to ground. The removal of the receiver at subscriber's station 1 closes the circuit in this path and actuates relays 16 and 21. The actuation of relay 21 closes its contacts 22 and 23 and the actuation of relay 16 closes its contacts 24 and 25. A circuit is thus completed from battery conductor 17, through the interrupter 27, the winding of motor magnet 28, conductor 29, contacts 25 and 24 of line relay 16, contacts 30 and 31 of cut-off relay 14, contacts 23 and 22 of cut-in relay 21, private conductor 33, segment 34, brush 35 and busy contacts 36, 37 and 38 of the distributing switch to ground, these busy contacts being grounded, as will be hereinafter described. The current in this path causes the operation of the motor magnet 28 and the step-by-step movement of the brushes of the distributing switch until the brush 35 arrives upon the non-grounded contact 39. At this time current flows from battery conductor 17, through interrupter 27, the coil 28 of the motor magnet, conductor 29, contacts 25 and 24 of line relay 16, contacts 30 and 31 of cut-off relay 14, conductor 42, now-closed contacts 43 and 44 and coil 45 of line relay 16, conductor 46 and the coil 47 of cut-off relay 14, to ground. The coil 47 of cut-off relay 14 is of high resistance as compared with the winding of motor magnet 28, and therefore the cut-off relay 14 is now actuated without giving an additional step to the distributing switch. Upon the actuation of cut-off relay 14 the circuit of the motor magnet 28 is interrupted at contacts 30 and 31 of cut-off relay 14 and a locking circuit is completed which maintains the actuation of relays 14, 16 and 21. This circuit may be traced as follows: from battery conductor 17, through the coil 48 of cut-off relay 14, the coil 49 of cut-in relay 21, conductor 50, contacts 51 and 31 of cut-off relay 14, conductor 42, contacts 43 and 44 and coil 45 of line relay 16, conductor 46 and the coil 47 of cut-off relay 14, to ground. The actuation of cut-off relay 14 closes its contacts 18 and 52, and 12 and 53, extending the

limbs 8 and 7 of the telephone line through contacts 54 and 55, and 56 and 57 of cut-in relay 21 to the segments 58 and 59 of the distributor switch. The segment 58 is now connected, through brush 60 and contact 61, with conductor 62 which connects with earth through contacts 63 and 64 of trunk cut-off relay 65, Fig. 2. The segment 59 is now connected through brush 67, contact 68, conductor 69, contacts 70 and 71 of trunk cut-off relay 65 and the coil of trunk relay 72 through conductor 73 to battery conductor 17. The current in this latter path and through the transmitter and receiver at the calling subscriber's station actuates trunk relay 72. The actuation of relay 72 closes its contacts 74 and 75, thus connecting the ground pole of battery through contacts 76 and 77 of relay 65, private conductor 78, contacts 39, brush 35, segment 34, conductor 33, contacts 22 and 23 of cut-in relay 21, conductor 42 and contacts 43 and 44 of line relay 16 to the coil 45 of that relay. The ground connection on the coil 45 of this relay shunts the current away from the coil 45 of relay 16 and the coil 47 of cut-off relay 14; line relay 16 therefore resumes its normal position but the cut-off and cut-in relays 14 and 21 are now maintained actuated from battery conductor 17, through coil 48 of relay 14, coil 49 of relay 21, conductor 50, contacts 51 and 31 of relay 14, contacts 23 and 22 of relay 21, conductor 33, segment 34, brush 35 and contact 39 of the distributor switch, conductor 78, contacts 77 and 76 of trunk cut-off relay 65 and contacts 74 and 75 of trunk relay 72, to ground. The closure of contacts 75 and 74 of relay 72 also places a ground connection upon all of the other private conductors extending to this particular operator's group. This circuit may be traced from ground, through contacts 75 and 74 of trunk relay 72, conductor 80, contacts 81 and 82 of key 83, common conductor 84, contacts 82 and 81 of keys 83 associated with other trunks, contacts 76 and 77 and private conductors 78 of all other trunks in this particular group not at that time busy, and the private contacts 39 of all of these trunks on their particular distributor switches. This places an artificially busy condition upon the contacts of the distributor switches to prevent other calls from being distributed before this particular operator until the call arising from subscriber's station 1 has been answered. The actuation of trunk relay 72 also closes contacts 86 and 87, completing a circuit from battery conductor 17, through the winding of the pilot relay 88, conductor 89, trunk line lamp 90 and contacts 87 and 86 of trunk relay 72, to ground. The current in this path lights the trunk lamp 90 to indicate to the operator that a call has arisen upon this particular trunk line. The

operator, observing the display of lamp signal 90, inserts the answering plug 92 of her cord circuit into the jack 93 indicated by the display of the lamp 90. The insertion of this plug into the jack closes a circuit from the live pole of battery A, through sleeve supervisory relay 94, conductor 95, sleeve contacts 96 and 97 of the plug and jack, conductor 98 and the coil of trunk cut-off relay 65, to ground. The current in this path actuates relays 94 and 65. The actuation of relay 65 severs the circuit of trunk relay 72 and contacts 70 and 71 of relay 65 and severs the ground connection of conductor 62 at contacts 63 and 64 of relay 65. The actuation of relay 65 also closes its contacts 99 and 77 and interrupts contacts 77 and 76. The ground connection is thus maintained upon private conductor 78, through contacts 99 and 77. The interruption of the circuit through trunk relay 72 permits that relay to fall back and open the circuit of the trunk lamp 90, thus effacing that signal. At the same time the ground connection is severed from conductor 80, thus freeing the common conductor 84 from its ground connection and permitting other calls to be received in this particular section of the switchboard. Since it is desirable to record the number of calls appearing before this particular operator, the relay 72 is provided with an additional pair of contacts 101 and 102, which, when closed, complete a circuit from battery conductor 17, through the winding 103 of relay 104, conductor 105 and contacts 102 and 101 of relay 72, to ground. The current in this path actuates relay 104, closing its contacts 106 and 107 in the circuit of the call counter 108, thus recording one call. It would not be desirable to permit the calling subscriber to record a large number of calls by moving his receiver hook up and down rapidly and thereby energizing and deenergizing trunk relay 72 and consequently the coil 103 of relay 104. Therefore a locking coil 109 is provided for relay 104, which maintains the actuation of that relay, if the subscriber hangs up his receiver, over the circuit which may be traced from battery conductor 17, Fig. 1, through the coil 48 of cut-off relay 14, the coil 49 of cut-in relay 21, conductor 50, contacts 51 and 31 of cut-off relay 14, contacts 23 and 22 of cut-in relay 21, private conductor 33, segment 34, brush 35 and contact 39 of the distributor switch, private conductor 78, contacts 77 and 76 of trunk cut-off relay 65, conductor 80, contacts 81 and 82 of key 83, common conductor 84, coil 109, and contacts 110 and 111 of relay 104, to ground. It will be seen, therefore, that relay 104, after once being actuated, will remain actuated whether relay 72 is actuated or not, until the operator has connected with the jack of the calling trunk and has actuated trunk cut-off relay 65. When this relay is actuated the circuit through the locking coil 109, of relay 104, is interrupted at contacts 76 and 77 of relay 65, and relay 104 therefore resumes its normal position, ready to record a second call when this operator's position is again selected. The resistance of the coil 109 of relay 104 is preferably made quite low, so that during the actuation of that relay the ground connection through contacts 111 and 110, the coil 109 of relay 104 and conductor 84 will be sufficient to bar other calls from coming in on any of the trunks extending to this particular group. 75

When a subscriber removes his receiver and then replaces it, and thus actuates relay 104, the operator's attention will be called by the flashing of the trunk lamp 90, and the operator can then depress her call-barring key 114 to complete a shunt about the coil 109 of relay 104 and again release that relay. If the operator does not notice the flashing of the lamp 90, relay 104 will be released when any regular manual subscriber makes a call in this particular operator's division by the actuation of pilot relay 115 which will be described later, and the closing of contacts 116 and 117 of that relay, thus connecting a shunt about the coil 109 of relay 104. 80

The connection of the operator's plug 92 with the jack 93 completes a circuit from the live pole of battery A through supervisory relay 94, sleeve conductor 95, sleeve contact 96 of the plug 100, and ring contact 118 of the jack 93, conductor 69, contact 68, brush 67 and segment 59 of the distributor switch, contacts 57 and 56 of cut-in relay 21, contacts 53 and 12 of cut-off relay 14, line conductor 7, transmitter 9, receiver 10, switch-hook 11, line conductor 8, contacts 18 and 52 of cut-off relay 14, contacts 54 and 55 of cut-in relay 21, segment 58, brush 60 and contact 61 of the distributor switch, conductor 62, the tip 105 contacts 119 and 120 of the jack and plug, conductor 121 and the coil of tip supervisory relay 122 to the ground pole of battery A. The current in this path increases the magnetization of supervisory relay 94 and actuates supervisory relay 122, thus preventing the answering supervisory lamp 123 from being displayed at this time. The operator now obtains the number of the desired subscriber's line in the usual way and 115 inserts her calling plug 124 into the jack of the desired line, whether this be a line provided with a distributor switch or a line of the ordinary manual type, the lines of different type being provided with the same 120 kind of multiple jacks. The insertion of the plug 124 into the jack of a regular line, as shown at the right of Fig. 3, closes a circuit from the live pole of battery A, through the coil of supervisory relay 125, 130

conductor 126, contacts 127 and 128 of the operator's ringing key, sleeve contacts 129 and 130 of the plug and jack and the coil of cut-off relay 131 to the ground pole of. 5 battery A. The current in this path actuates cut-off relay 131, moving its contacts to their abnormal positions and thus separating the limbs 7 and 8 of the telephone line from their normal connection 10 with battery and ground. The actuation of relay 125 closes its contacts 132 and 133, thus completing the circuit of the calling supervisory signal 134 to display that signal. The operator now depresses her ringing 15 key and connects the alternating current generator 138 with the tip of the calling plug. The current therefore passes over the tip contacts 139 and 140 of the calling plug and jack, line conductor 8, ringer 6, condenser 5, 20 line conductor 7, ring contact 141 of the jack and contact 129 of the plug, contacts 128 and 142 of the operator's ringing key and the non-inductive resistance 143 to battery conductor 17 and thence back to the 25 generator 138. The current in this path passes through condenser 5 and actuates the bell at the desired subscriber's station. When the desired subscriber answers his 30 call a circuit is completed from the live pole of battery A, through the coil of supervisory relay 125, conductor 126, contacts 127 and 128 of the operator's ringing key, sleeve contact 129 and ring contact 141 of the plug and jack, line conductor 7, transmitter 35 9, receiver 10, contacts of switch-hook 11, line conductor 8, tip contacts 140 and 139 of the jack and plug, series contacts 144 and 145 of the operator's ringing key, contacts 146 and 147 of the operator's listening 40 key, conductor 148 and the coil of tip supervisory relay 149, to the ground pole of battery A. The current in this path actuates the tip supervisory relay 149 and effaces the supervisory signal 134. The calling and 45 called subscribers are now in conversation and all signals are in their unactuated condition at the central office. When these subscribers replace their receivers upon their respective switch-hooks the circuits through 50 tip supervisory relays 122 and 149 are severed and the supervisory lamps 134 and 123 are displayed, the display of these signals indicating to the operator that the conversation has been terminated and that the 55 plugs should be removed from the jacks with which they are connected.

The circuit of the answering supervisory signal 123 is carried through conductor 151 and the coil of pilot relay 152. This relay 60 has normally open contacts 153 and 154, adapted when closed to ground the common conductor 84, which, as formerly explained, prevents calls from being received on the trunk lines appearing in this particular 65 group, the purpose of this being to make

the operator prompt in removing the plugs from the jacks at the termination of a conversation. The undistributed lines with which this same cord circuit may be connected for answering regular manual calls 70 may be of the type just described and shown at the right-hand side of Fig. 3. The line extending to subscriber's station 3 is of this character, the limb 7 of this line passing normally through the coil of a line relay in 75 the manner well known in the art. The actuation of this line relay, upon the removal of the receiver from the switch-hook at the subscriber's station 3, closes its contacts 156 and 157, thus completing the circuit of the line lamp 158 in the usual manner. The circuit of this line lamp extends through conductor 159 and the coil of pilot relay 115 so that the actuation of this line lamp, or the lamp of any other line terminating at this particular position in the switchboard, will cause the actuation of relay 115. The actuation of this relay closes its contacts 116 and 117, placing ground upon the common conductor 84 and thus 80 preventing any of the trunk lines extending to this particular operator's group being selected by any of the distributor switches. Relay 115 also has normally open contacts 160 and 161, which complete the circuit of 85 the pilot lamp 162, which is displayed whenever a call, either regular or distributed, appears in this particular operator's group.

It is to be understood that the calling plug 124 may be inserted into the multiple 100 jack of one of the lines provided with a distributor switch. When this is done the operation of the cord circuit and of the relays associated therewith is exactly the same as when the cord is connected with a regular 105 manual line. The cut-off relay 14 is pulled up in the same manner as cut-off relay 131 of the manual line. The circuit for actuating this cut-off relay 14 may be traced from the live pole of battery A to the coil of 110 supervisory relay 125, sleeve conductor 126, contacts 127 and 128 of the operator's ringing key, sleeve contact 129 and ring contact 170 of the plug and jack, conductor 171, contacts 56 and 172 of cut-in relay 21, 115 conductor 46 and the coil 47 of cut-off relay 14, to ground. The current in this path actuates cut-off relay 14, connecting the limbs of the telephone line directly with the tip and ring contacts of the jack. The sleeve 120 contacts of these multiple jacks are preferably connected directly with the ring contacts so that the busy condition is established upon the multiple in the case of incoming calls as soon as an idle trunk has 125 been selected.

If, in case of an extreme rush of calls, it is desired to allow the distributed calls to appear before the operators even though they already have unanswered calls before 130

them, the buttons 83 may be pressed, thus individualizing each of the trunk lines so that neither regular manual calls nor other distributed calls will connect ground battery with the private conductors of the various trunks. Thus the calls will be received on any trunk line which is not actually busy itself.

Each operator's position is preferably divided into two groups, and each group is preferably equipped with the apparatus shown and described herein. While I do not desire to limit my invention to two groups, this number will be found to be convenient as in this manner the operator may have a distributed call in each group simultaneously and thus she may, during the busiest period, have one call ahead of her at all times—that is, a call may appear in one group while she is answering a call in the other group, and a second call may appear in the second group while she is answering the call in the first group. If only one group per operator is used a slight loss of time will occur between calls, and if more than two groups are used the subscribers will be required to wait too long before their calls can be attended to.

It will be seen that my system is applicable to extensions to manual exchanges which are now equipped with regular multiple circuits. In a regular manual multiple system, when a large number of lines terminate before an operator, it frequently occurs that a rush of calls will not only use up all of the operator's available cord circuits, but will, in addition, so overwork the operator that subscribers will be required to wait longer for replies to their calls than could be expected of the most patient subscriber. With my system, however, the number of regular subscribers' lines terminating before any operator is kept to such a minimum that the operator can answer the calls during the rush periods, not only without using up all of her cord circuits, but without making it necessary for subscribers to wait a considerable length of time before their calls are answered. It seldom happens that the rush period occurs before all operators simultaneously, and with my system an operator who is rushed by reason of a large number of calls on her regular manual subscribers' lines does not receive any of the calls which come in upon the distributed lines until all of the manual calls have been answered. If, then, the operator's cord circuits are almost exhausted she may depress her total barring button and thus prevent any distributed calls from appearing in her position, these calls being given to operators who are at that time caught up with their calls and who have available cord circuits.

It sometimes happens that an operator is unavoidably drawn into an extended con-

versation with the subscriber, which may last several seconds, and during this time it is convenient for the operator to depress her total barring button 114 and thus prevent calls from being distributed to her position 70 at this time.

It will be found that with this system the operators' loads in calls per hour will be nearly equalized and, therefore, that the number of operators for answering a given 75 number of calls can be considerably reduced since all of these operators will be worked up to substantially the limit of their speed at all times, and there will never be operators who have scarcely any calls to answer 80 while other operators are greatly rushed.

While I have shown and described my invention with respect to certain definite and well-known manual systems, it is to be understood that it may be applied to other systems and that the specific circuit arrangements may be largely altered without in any way departing from the spirit or scope of my invention.

I claim:

1. In a telephone system, the combination with an operator's connective means controlled by a connecting operator, of a telephone line extending from a sub-station to the central office and permanently terminating in a connective means at said connecting operator's position, a second telephone line extending from a sub-station to the central office and automatic distributing means for extending it to any one of a plurality of 100 operators' positions, and means to prevent said line from being extended to said operator's position when an unanswered call exists upon the other line.

2. In a telephone system, the combination with an operator's connective means controlled by a connecting operator, of a telephone line extending from a sub-station to the central office and permanently terminating in contacts at said connecting operator's position, a second telephone line extending from a sub-station to the central office and means for automatically extending it to any one of a plurality of operators' positions, said means acting to extend said line to another operator's position when an unanswered call exists on the first telephone line.

3. In a telephone system, the combination with telephone lines extending from subscribers' stations to operators' positions at a central office, other telephone lines extending from subscribers' stations to the central office and trunks extending to said operators' positions, and automatic means for associating any of said trunks with any of said telephone lines, and further means to prevent the association of a line and a trunk extending to an operator's position at which an unanswered call exists upon one of the first lines or one of the trunks.

4. In a telephone system, the combination with undistributed telephone lines and trunks leading to the same operator's group, other telephone lines and means for vari-
5 ously connecting them with said trunks, and means for preventing the use of said trunks when an unanswered call exists upon an undistributed telephone line extending to said group.
- 10 5. In a telephone system, the combination with undistributed telephone lines and trunks leading to the same operator's group, other telephone lines and means to connect them with said trunks, and means for pre-
15 venting the use of said trunks when an unanswered call exists upon an undistributed telephone line or upon a trunk extending to said group.
- 20 6. In a telephone system, the combination with a plurality of telephone lines, of a switch for each of said lines, multiple contacts for said switches connected with trunks, and a plurality of operators' groups to which said trunks extend, motor-mech-
25 anism for said switches adapted to rotate the same in one direction only, an undistributed telephone line extending to one of said operators' groups, and means to cause the ac-
30 tuation of said motor-mechanism to rotate said switches to prevent the connection of any one of the first telephone lines with the trunks extending to said group when an un-
35 answered call exists on said undistributed telephone line.
- 40 7. In a telephone system, the combination with a plurality of telephone lines, of an-
45 swering jacks permanently associated with certain lines, trunk jacks and means to automatically associate them with certain lines, said answering jacks and trunk jacks being in the same group, and means to prevent the trunk jacks from being automatically associated with one of said lines when an un-
50 answered call appears upon one of the an-
55 swering jacks in said group.
- 55 8. In a telephone system, the combination with a plurality of telephone lines, of a plu-
60 rality of groups of line terminals at the central office permanently associated with said lines, a second plurality of telephone lines and a second plurality of terminals in said groups, and means to automatically connect one of the second plurality of lines with one of the second plurality of terminals, and means to prevent a line of the second plu-
65 rality from connecting with a terminal of the second plurality in a particular group when an unanswered call from either plu-
70 rality of lines appears in said group.
- 75 9. In a telephone system, the combination with a pair of telephone lines, of an an-
80 swering jack permanently associated with one of said lines, a trunk jack, and means for automatically associating it with the other
85 of said lines, and means to prevent the auto-
90 matic association of the second jack and line when an unanswered call exists upon the jack of the first line.
- 95 10. In a telephone system, the combination with three telephone lines, of an answering jack and lamp permanently associated with one of said lines, a pair of jacks and lamps and means to automatically associate them with the other pair of lines, and means to prevent one of the latter lines from being automatically associated with one of the jacks and lamps when either of the other two lamps is displayed.
11. In a telephone system, the combination with a telephone line, of a lamp therefor at the central office adapted to be displayed when an unanswered call exists upon said line, a second telephone line, a lamp automatically associated therewith and displayed when an unanswered call exists upon this second telephone line, a third telephone line and a third lamp, and means which may automatically associate said third line and said third lamp when a call exists upon the third telephone line, and means whereby the existence of an unanswered call upon either of the first telephone lines prevents the automatic association of said third line and the third lamp.
12. In a telephone system, the combination with a telephone line, of a jack and lamp permanently associated therewith at the central office, a second telephone line, a distributer switch, and a jack and lamp adapted to be associated with said line through the medium of said distributer switch, a private conductor associated with said distributer switch, means actuated during the display of said first lamp to place an electrical condition upon said private conductor to prevent the distributer switch from connecting the second line with the second jack.
13. In a telephone system, the combination with a pair of telephone lines, of an answering jack permanently associated with one of said lines, a distributer switch for the other of said lines, a plurality of talking and private contacts for said switch, brushes registering with said contacts, means causing the rotation of said switch when the latter line is closed at the substation and the private brush is registering with a grounded private contact, and means associated with the first telephone line for grounding one of the private contacts of said switch when the receiver is removed from the switchhook at the substation of said line.
14. In a telephone system, the combination with an undistributed telephone line, of a distributed telephone line, a distributer switch therefor, terminals for the distributed line appearing at the same section of the switchboard in which terminals for the undistributed line appear, and means whereby the existence of an unanswered call upon the

the terminals of the undistributed line prevents the extension of the distributed line to terminate in said section.

15. In a telephone system, the combination with automatic distributor switches and automatically distributed and undistributed telephone lines, of means whereby unanswered calls on the undistributed telephone lines affect the automatic distribution of calls upon the distributed telephone lines.

16. In a telephone system, the combination with undistributed telephone lines, of distributor switches, trunks extending from said distributor switches, and means whereby unanswered calls upon the undistributed telephone lines bar calls upon said trunks.

17. In a telephone system, the combination with a plurality of telephone lines, a plurality of trunk lines, automatic means for connecting any of said telephone lines with any of said trunk lines, a cord circuit for extending said trunks into connection with desired ones of said telephone lines, supervisory signals, one for each of said cord circuits, means to display said signals when the calling subscriber of a connection severs the telephone line at his substation, said means serving also to prevent other telephone lines from being connected with other trunk circuits during the display of said signal, and means to efface said signal.

18. In a telephone system, the combination with telephone lines, of distributor switches therefor, contacts of said switches extending to the same operator's position, an answering supervisory signal at said operator's position displayed at the termination of a conversation to indicate that the connection should be taken down and means

40 to prevent calls being distributed to an operator's position after a conversation has been terminated and before the connection has been taken down.

19. In a telephone exchange system, the combination with a plurality of telephone lines upon some of which a large number of

calls are originated, and upon others of which a small number of calls are originated, of a plurality of operator's positions at which the lines originating a small number of calls permanently terminate in connecting devices so that each operator attends to substantially an equal number of lines originating few calls, and automatic means for distributing the calls received upon the lines originating a large number of calls before the various operators of the exchange who are not busy answering the permanently terminated lines, whereby the work of the various operators is substantially equalized.

20. In a telephone exchange system, the combination with a switchboard, of a plurality of operators' positions, a plurality of lines permanently terminated at each operator's position, a second plurality of lines and means to automatically extend them to the various operators' positions, the automatically extended lines being of sufficient number so that when the calls received thereon are automatically distributed to non-busy operators the work of all of the operators is substantially equalized.

21. In a telephone system, the combination with a division of a switchboard, of telephone lines permanently terminating in answering jacks at said division of the switchboard, trunk lines terminating at said division of the switchboard, an automatic switch for furthering a connection between a calling line and one of said trunks, and means at said division of the switchboard controlled by the condition of said lines for preventing the automatic connection of said trunk with a calling line.

Signed by me at Rochester, county of Monroe, and State of New York, in the presence of two witnesses.

HENRY P. CLAUSEN.
